RECEPTACLE

William B. Hirshon, Chelsea, Mass.

Application December 12, 1931, Serial No. 580,922

1 Claim. (Cl. 217—31)

The present invention relates to receptacles such as egg cartons and is more particularly concerned with the construction of the filler which divides the container into compartments or cells. The primary object of the present invention is the provision of a filler for an egg carton or the like of such construction as to expose to view a relatively large portion of the egg in each cell for display purposes and to afford the prospective purchaser a better opportunity to inspect the eggs offered for sale.

Another object of the invention is to improve the interlock device between intersecting filler strips.

Another object of the invention is to provide improved cushioning means in the egg carton at the four sides thereof.

A further object of the invention is generally to improve receptacles of the egg carton type and the fillers therefor.

For a complete understanding of the invention reference is to be had to the following description and the accompanying drawing, in which:

Figure 1 is a longitudinal sectional view of the 25 carton having the improved filler thereon on the line 1—1 of Figure 2;

Figure 2 is a plan view on the line 2—2 of Figure 1;

Figure 3 is a sectional view on the line 3—3 of 30 Figure 1;

Figure 4 is a fragmentary sectional view on the line 4—4 of Figure 3;

Figure 5 is a side view of one of the filler members; and

Figure 6 is a fragmentary side view of a companion filler member.

As here shown, the receptacle is made of paper or any other suitable material and comprises a box or casing 10 having a cover flap 11, and intersecting filler strips 12 and 13, which divide the box 10 into a plurality of cells or compartments, as shown more clearly in Figure 2. The companion strips 12 and 13 project beyond the cells as at 14 and 15, forming cushioning compartments 16 at the four sides of the box thereby protecting the eggs against breakage.

As shown in Figures 5 and 6, the filler strips 12 and 13 are provided with cut-out portions or recesses 17 and 18 respectively at their upper edge portions and similar recesses 19 and 20 respectively at their lower edge portions, and by reason of certain cut-outs the egg in each compartment or cell in the box is exposed at the major top portion thereof on all sides. The cut-out portions at the bottom edge portions of the filler strips 12 and 13 make certain a similar display of the eggs should the filler strips be exposed in the box reversely with respect to the upper and lower edge portions of said strips.

According to the present invention strips 12 and 13 are assembled in intersecting relation and are held in this relative position by an interlock construction. For this purpose each strip 12 is provided with slits at 21 terminating in the cut-out portions 22 forming tongues 23 of the form shown more clearly in Figures 4 and 6, and each strip 13 is provided with slits 24 and spaced vertically-aligned, cut-outs 25. As thus constructed, the strips are assembled so that the slits 21 of the 10 strips 12 are disposed at the upper portions of the strips 13 and the slits 24 of the strips 13 are disposed at the lower portions of the strips with the tongues 23 engaging the strips 13 in the recesses 25.

As shown more clearly in Figures 4 and 6, the edges of each strip 12 at the slit 21 are straight above the tongue 23 and are curved at and below said tongue. The edge of the tongue 23 and the opposed edge 23' converge forming a slit that 20 is gradually restricted to a maximum at the lower edge 23a of the tongue. Thus, the slit 21 is widest at the top and narrowest at the bottom where it merges into the recess 22. This construction facilitates assembly of the strips 12 and 13 and prevents their accidental separation. The tongues 23 are provided with overhanging portions 23a which extend over the portions of the strips 13 adjacent the openings 25 and thereby aid 30 in preventing accidental separation of the strips 12 and 13. The bottom edges of the overhanging portions 23a of the tongues 23 are downwardly inclined and engage the bottom edges of the openings 25 in the companion strips 13. Thus, the restricted slits 21' and the overhanging tongue portions 23a cooperate to improve materially the 35 interlock construction between the strips 12 and 13.

While I have shown and described the preferred embodiment of my invention, it will be understood 40 that certain changes in the construction and arrangement of parts may be made without departing from the present invention. Therefore, I do not wish to be limited to the exact construction shown, except as may be required by the 45 appended claim and the prior art.

Having thus described my invention, what I claim is:

Filler strips for egg cartons comprising strip members having vertically disposed slits and 50 tongues, companion strip members having vertically disposed slits and aligned spaced recesses, said tongues engaging said companion strip members in said recesses, all said strip members having cut-out portions in the upper edge portions 55 thereof located between said slits, said cut-out portions being of such size as to expose the major top portions of the eggs on all sides thereof.
